(57) **CLAIM**

The ornamental design for a sensor module, as shown and described.

DESCRIPTION

This application makes reference to:
U.S. Design application Ser. No. 29/491,674 filed May 22, 2014.

The above referenced application, and all of the subject matter disclosed therein, is incorporated herein by reference in its entirety.

FIG. 1 is a top left front perspective view of a sensor module showing our new design;

FIG. 2 is a rear elevation view thereof;

FIG. 3 is a front elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a bottom right rear perspective view thereof.

The even length dashed broken lines are for environmental purposes only and form no part of the claimed design.

The uneven length dot-dash broken lines represent an unclaimed boundary line and form no part of the claimed design.
